CLAIM

I claim the ornamental design for a light, as shown and described.

DESCRIPTION

FIG. 1 is a Perspective view of a light showing my new design;

FIG. 2 is a Front view of the light as shown in FIG. 1;
 FIG. 3 is a Back view of the light as shown in FIG. 1;
 FIG. 4 is a Left-side view of the light as shown in FIG. 1;
 FIG. 5 is a Right-side view of the light as shown in FIG. 1;
 FIG. 6 is a Top view of the light as shown in FIG. 1; and,
 FIG. 7 is a Bottom view of the light as shown in FIG. 1.
 The broken lines are only for environmental purposes and
 form no part of the claimed design.
